UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WINDING MACHINE.

Application filed May 22, 1922. Serial No. 562,606.

To all whom it may concern:

Be it known that I, ALONZO E. RHOADES, a citizen of the United States, and resident of Hopedale, county of Worcester, State of Massachusetts, have invented an Improvement in Winding Machines, of which the following description, in connection with the accompanying drawing, is a specification, like characters on the drawing representing like parts.

This invention relates to a machine for winding yarn upon a yarn receiver in the nature of a spooler.

The object of the invention is to provide a machine which will wind simultaneously yarn from a plurality of yarn carriers such as bobbins onto a corresponding plurality of yarn receivers to enable large masses of yarn to be wound onto the receivers by piecing the ends of successive yarn carriers and in which the yarn shall be wound upon the yarn receivers with a "filling wind."

The object of the invention is to provide a simple and efficient mechanism in a winding machine of this type which will produce the desired "filling wind" on the yarn receivers.

The nature and objects of the invention will appear more fully from the accompanying description and drawings and will be particularly pointed out in the claims.

In the drawings:

Fig. 1 is a front elevation of a portion of a winding machine embodying a preferred form of the invention with only such parts illustrated as are necessary to a disclosure of the invention;

Fig. 2 is a view in transverse vertical section of the construction shown in Fig. 1;

Fig. 3 is a detail in plan view of a portion of the pick motion mechanism.

This invention is particularly designed for winding large masses of yarn with a filling wind upon receivers in the form of spools having but one head. It is desirable to have such large masses of yarn wound with this filling wind upon spools of this type particularly in connection with the manufacture of cords such as are employed in automobile tires. The yarn from several of the receivers wound in accordance with this invention is twisted together to form a strand and several of these strands in turn are twisted together to form the desired cords. In these operations it is found desirable to have the yarn in as long continuous strands

as possible and the operation is much facilitated if these strands of yarn can be drawn off from the end of the spool rather than off from the side as is the case when the warp wind is employed.

The winding machine herein illustrated as a preferred embodiment of the invention in its general make up, that is except for the provision of means for securing the filling wind, is of the same general construction as a familiar type of spooler. But in the case of the spooler the yarn is wound from the bobbins onto the spools with a warp wind, that is to say the yarn is laid on the spools in successive cylindrical layers, so that when it is drawn off from the spool the spool rotates on its axis and the speed of rotation of the spool and the tension of the yarn varies continuously throughout the entire unwinding operation. In this invention wherein means are provided for producing a filling wind upon the yarn receivers or spools the yarn is unwound therefrom by drawing it off in line with the axis of the spool, there is no rotation of the spool, and while the tension on the yarn varies somewhat as each conical layer comes off the tension subject to this variation remains the same throughout the entire unwinding operation.

In this type of winding machine the yarn receivers or spools are preferably arranged in two rows extending along the front and the back of the machine and the yarn carriers which feed the yarn to the spools are arranged in two corresponding rows and the operation of winding goes on simultaneously with respect to all of the yarn receivers or spools.

The frame of the machine comprises suitable supporting uprights 1 connected longitudinally by beams 2 and rods 3. Longitudinal members of the frame are connected transversely by suitable cross struts 4. All of these members may take any suitable and desired form. Each yarn receiver as employed in this invention consists of a single head 5 and a barrel 6 provided with a conical base connecting it to the head. Each of these spools is mounted on a spindle driven by a whorl 7 and these whorls and spindles are located as noted in two rows on top of the beams 2. A winding rotation is imparted to each of the whorls 7 by bands 8 extending about a drum 9 mounted on the main shaft 10 extending longitudinally of the ma-

chine. Power is communicated to the shaft 10 in any suitable manner as through the fast and loose pulleys 11, 12.

The yarn carriers are shown in the form 5 of bobbins 13. Each bobbin is mounted in a holder opposite each spool. This holder may be of any suitable form and one familiar form is herein illustrated comprising a bracket 14 secured to the rods 15 extending 10 longitudinally of the machine in front of the beams 2, a bed or seat 16 upon which the bobbin rests and a suitable tension or controlling device 17. The yarns extend 15 from the respective bobbins 13 to the corresponding spools and run through suitable guides 18.

The guides 18 are mounted on traverse rods 19 extending longitudinally of the machine in front of the spools. These traverse rods 19 are supported by lifting mechanism 20 through which is given the necessary traverse motion.

The lifting mechanism in the form illustrated 25 comprises a plurality of yoke-shaped members 20, the upper horizontal ends of which are pivoted at intervals along the beams 2 at 21 on uprights 22 carried by the beams. On each pivotal point 21 are mounted arms 23 which are connected by links 24 to the traverse rods and projections 25 extend from the yoke-shaped members 20 beneath the arms 23. It will thus be seen that 30 if the yoke-shaped members 20 be swung clockwise about their pivots 21 the traverse rods 19 with the traverse guides 18 will be raised and that if the yoke-shaped members 20 be swung in the opposite direction, as by the weight of the traverse rods and connected parts, the traverse rods will be 35 lowered.

In this invention the movement given to the lifting mechanism is such as to provide the desired filling wind. This is caused by 40 giving the traverse rods and the traverse guides carried thereby a fixed length of traverse and by progressively shifting the zone of traverse during the winding operation until that operation is completed. Thus during each complete traverse the width of the zone of yarn wound upon the receiver is the same but as this zone is progressively shifted throughout the length of the spool the entire spool is finally covered with the 45 desired filling wind.

A simple and preferred form of mechanism for effecting this required movement of the lifting mechanism for the traverse rods is illustrated. The lower ends of the yoke-shaped members 20 are connected by a rod 26 extending longitudinally of the machine. A bell crank lever 27 is mounted at the bottom of the frame with one arm 28 extending vertically and the other arm 29 extending horizontally. As illustrated this bell crank lever 27 is fulcrumed on a shaft

30 journalled in bearings 31 resting upon the rods 3 and connected by the cross piece 32 held in place by the bracket 33.

The upper end of the arm 28 of the bell crank lever is bifurcated transversely and 70 between the bifurcations thereof is journalled at 34 a drum 35. A flexible connector in the form of a chain 36 is connected at one end to the drum 35 and at the opposite end to the rod 26. As illustrated a suitable adjustable connection 37 is interposed between the end of the flexible connector or chain 36 and the rod. It will thus be seen that if the bell crank lever 27 is rocked on its fulcrum 30 the traverse rods 19 with the 75 traverse guides 18 will be raised and lowered. This rocking movement is effected by means of a cam cooperating with the free end of the arm 29 of the bell crank lever and driven preferably from the main shaft of 80 the machine.

In the construction illustrated a bracket 85 38 is bolted to a suitable portion of the frame such as the uprights 39. This bracket carries horizontally projecting arms 40 in which is journalled a vertical shaft 41 carrying a worm wheel 42 and a connected barrel cam 43 which is the cam engaging and operating the free end of the arm 29 of the bell crank lever. A roller 44 is journalled 90 in the end of the arm 29 to bear against the face of the cam 43.

The worm wheel 42 is rotated by a worm 45 carried on a shaft 46 journalled at one 100 end on a bracket 47 bolted to the frame and at the other end on a bracket 48 projecting from one of the uprights 1. This shaft is rotated in any suitable manner and for that purpose a sprocket chain 49 is illustrated 105 by which the rotation of the main shaft 10 rotates the shaft 46. With the mechanism thus far illustrated and described the width of the zone of traverse imparted to the traverse rods 19 and traverse guides 18 would 110 remain constant. In order to secure the progressive shifting of the zone of traverse a pick motion mechanism is provided. In the form illustrated a bracket 50 is bolted to the arm 28 of the bell crank lever and this bracket has journalled thereon preferably 115 in an inclined direction a shaft 51 carrying at its lower end a worm 52 which meshes with a worm wheel 53 connected to and rotating with the drum 35. The upper end of the bracket 50 is formed to present a bifurcated portion 54 in which is journalled a transverse shaft 55 carrying a beveled gear 56 meshing with a beveled gear 57 on the upper end of the shaft 51. There is also mounted 120 on the shaft 55 a ratchet wheel 58. It will thus be seen that if the ratchet wheel 58 is rotated rotation will also be imparted to the drum 35 and the chain 36 will be wound upon the drum thus shortening the 125 distance between the axis of the shaft 34 and

point at which the chain is connected to the rod 26 thus shifting upwardly the zone of traverse imparted to the traverse rods 19 and traverse guides 18.

5 The rotation of the ratchet wheel 58 is imparted by the engagement of the ratchet wheel, as the bell crank lever 27 is swung, with a relatively fixed pawl 59. This pawl is shown as adjustably connected at its pivot 10 to a point 60 in a slot 61 to a bracket 62 secured to one of the beams 2.

With the construction thus illustrated each time the bell crank lever 27 is swung clockwise by the cam 43 the ratchet 58 engages 15 the pawl 59 and winds the chain 36 upon the drum 35 thus shifting the zone of traverse and the extent of this shifting movement is determined by the longitudinal adjustment of the pawl 59.

20 When the winding operation is completed and it is desired to restore the traverse rods 19 to a lowermost position the pawl 59 is elevated to disengage the ratchet 58 and the drum 35 is unwound to lengthen out the

25 chain 36. To enable this to be done readily a hooked rod 63 engaging beneath the pawl 59 and mounted in the flange of the beam 2 is pulled upwardly and locked or held in elevated position. The ratchet wheel is then

30 rotated to unwind the chain. To enable this rotation of the ratchet to be performed readily a sprocket wheel 64 is mounted on the shaft 55 and a sprocket chain 65 runs thereover and about a sprocket wheel 66

35 journaled in the arm 29 of the bell crank lever. A key may now be placed in the end of the shaft 67 of the sprocket wheel 66 and rotation thus imparted to unwind the drum 35 and chain 36.

40 Having thus described my invention what

I claim as new and desire to secure by Letters Patent, is:

1. A winding machine comprising a frame, a series of yarn receivers and means for rotating them, a series of yarn carriers, a 45 traverse rod provided with guides through which the yarn passes from the respective yarn carriers to the corresponding yarn receivers, lifting means for the traverse rod, a bell crank lever fulcrumed on the frame, a 50 drum journalled on one end of the bell crank lever, a flexible connector connected to the drum and to the traverse rod lifting mechanism, a cam acting on the other end of the bell crank lever, means for rotating the cam to rock the bell crank lever and thereby effect a filling traverse of fixed length, and a pick motion mechanism mounted on the bell crank lever, actuated upon the rocking of the bell crank 55 lever to give a partial winding rotation to the drum and thereby effect a progressive shift of the zone of traverse during the winding operation, whereby the yarn is wound onto the receivers with a filling wind. 60

2. A winding machine comprising the construction defined in claim 1 in which the pick motion mechanism comprises a worm wheel on the drum, a shaft having a worm 70 engaging the worm wheel, a ratchet wheel, and gearing interposed between the ratchet wheel and shaft and in which a pawl is mounted on the machine frame and co-operates with the ratchet to effect its partial rotation upon the rocking of the bell crank 75 lever.

In testimony whereof, I have signed my name to this specification.

ALONZO E. RHOADES.
